UNITED STATES PATENT OFFICE.

JOHN M. JACKSON, OF KANSAS CITY, KANSAS.

APPARATUS FOR REMOVING WALL-PAPER.

1,164,940.

Specification of Letters Patent. Patented Dec. 21, 1915.

Application filed June 21, 1913. Serial No. 775,060.

To all whom it may concern:

Be it known that I, JOHN M. JACKSON, a citizen of the United States, residing at Kansas City, in the county of Wyandotte and State of Kansas, have invented new and useful Improvements in Apparatus for Removing Wall-Paper, of which the following is a specification.

The present invention relates to apparatus for removing wall paper, and includes such component elements which obviously illustrate the efficiency of the device.

It is the primary object of this contrivance, therefore, to provide novel means for 15 ejecting the paper loosening medium thereagainst, and as a sequence the latter may be quickly and easily removed.

The medium employed is primarily designed to impregnate the paper and liquefy 20 the securing paste; yet it is apparent that this operation will, at the same time, destroy all germ life contacted therewith, and thus provide thoroughly cleaned, sanitary walls.

Experimentation has adduced, that steam under pressure is best suited for the purpose of impregnating the paper, its velocity being of such sufficiency to cause the steam to thoroughly saturate the paper and liquefy 30 the securing paste, and at the same time destroy all germ life.

Other objects will appear as the description continues.

The above and other objects in view, my 35 invention relates to such details of construction and in the arrangement and combination of parts, as will be hereinafter fully described and specifically pointed out in the appended claims.

In describing my invention in detail, reference will be had to the accompanying drawings, wherein like characters designate like or corresponding parts throughout the several views, and in which:

Figure 1 is a side elevation of my invention. Fig. 2 is a fragmentary view of the nozzle operating rod, illustrating hand grips thereon.

Referring now more particularly to the 50 drawings, wherein is shown the preferred embodiment of my invention, I have provided improved means generating steam and conducting the same to the ejecting nozzle. Respecting the above, a boiler 10 is provided, the same being supported through the medium of a plurality of contingent sections

11, the latter being connected at their lower extremities and formed into an annular flange 12, as shown.

The upper extremity of the boiler is 60 closed through the medium of a cover 13, the latter being securely fastened thereto through the medium of spaced rivets 14, as illustrated. A water glass 15 is supported upon the boiler interjacent its extremities, 65 through the medium of the valve elements 16, a plurality of brace rods 17 also being included for assuring the rigidity of the structure. The water glass is used to determine the amount of water in the boiler, and 70 therefore it will be recognized that its provision is absolutely essential.

With view of determining the pressure within the boiler, a pressure gage 18 is provided, the latter having connection with the 75 boiler through the medium of a vertical rod 19 and connecting joint 20, the latter being in screw threaded engagement therewith, as clearly shown. A second joint 21 is provided upon the cover, the latter connecting a 80 safety valve 22, actuation of which is controlled by a pivoted lever 23 carrying an adjustable weight 24. This lever is provided in view of increasing and decreasing the weight upon the safety valve, thus allowing 85 the same to be set at any degree desired.

Interposed between the sections 11 and secured directly beneath the bottom of the boiler, I have provided a burner 25, of the usual crude oil type, the latter being fed 90 through the medium of a fuel pipe 26, which extends vertically above the boiler and is secured thereto through the medium of a bracket 27. A cut-off valve 28 is provided in the pipe in proximity to the sections 11, 95 in order that the supply of fuel in the boiler may be cut off or increased when desired. For feeding the fuel pipe, and consequently allowing the burner 25 to be lighted, a fuel reservoir 29 is provided on the upper end of 100 the pipe, as shown, the same carrying the fuel desired.

After steam has been generated in the boiler, I find it desirable to provide suitable conducting means which are of such type as 105 to eject the steam evenly upon the walls acted on and at the points desired. With this in view, I have provided upon the cap 13 of the boiler a vertical pipe 29 having a valve 30 mounted interjacent its extremity 110 for the purpose of controlling the passage of steam therethrough. A flexible hose 31

has connection with the upper extremity of the pipe 29, as at 32, the other end of the hose being secured, as shown at 33, to a conducting pipe 34. With view of supporting a transverse, perforated tube 35, the forward extremity of the pipe 34 is provided with a T joint 36, as shown, consequently providing a compact nozzle, of such type as above mentioned.

10 The steam flowing through the pipe 34 will heat the same to a considerably high temperature and, in order to avoid injury to the operator's hands, I have provided thereon hand grips 37 and 38, the first mentioned grip being secured fast thereto, as shown at 39, while the other grip is slideable, in order to facilitate the vertical oscillations of the nozzle.

15 In the operation of my invention, the burner 25 is first lighted and allowed to burn until the steam within the boiler has reached a pressure of 40 or 45 degrees. The valve 30 is now opened which will allow the steam to escape through the hose 31 to the tube 35; the operator now grasps the hand grips in an obvious manner and guides the transverse tube 35 over the paper acted on, consequently completely saturating the latter and liquefying the securing paste.

20 After the paper has been thoroughly saturated the operator takes hold of one end thereof and it will, without the material exertion of any pressure, fall from the wall.

25 The advantages resultant from the use of my invention are thought to be readily

comprehended by those conversant with the crude and unsatisfactory devices heretofore provided in this art.

Such changes as are permissible by the subjoined claims may be resorted to without departing from the spirit of my invention.

Having thus fully described my invention, what I claim as new and desire to secure by Letters Patent, is:

40 1. A wall paper remover including a tubular rod forming a handle, a T-coupling carried by the free end portion of said rod, pipes carried by said coupling and provided with longitudinally extending rows 50 of openings constituting outlets, and means for closing the ends of said pipes.

2. A wall paper remover including a tubular rod forming a handle, and a perforated cross pipe connected with said handle 55 and forming an applying nozzle.

3. A wall paper remover including a tubular rod forming a handle, a T-coupling carried by the free end portion of said rod, pipes carried by said coupling and having their forward sides provided with longitudinally extending rows of openings constituting outlets, means for closing the end 60 of said pipes, a rigid hand grip mounted upon said handle, and a movable hand grip 65 mounted upon said handle.

JOHN M. JACKSON.
